ORNAMENTAL METALWORK PANEL

Herman Harris Carter, Dallas, Tex.

Application July 7, 1955, Serial No. 36,860

Term of patent 14 years

(Cl. D54—2)

Fig. 1

Figure 1 is a front elevational view of an ornamental metalwork panel showing my new design, the rear thereof being of the same; and

I claim:

The ornamental design for an ornamental metalwork panel, substantially as shown and described.
